PLASTIC SEAL MACHINE

Eyrle Robert Levy, San Francisco, Calif.

Application May 26, 1951, Serial No. 228,519

5 Claims. (Cl. 226—80)

1

This invention relates to a machine for applying bands to the neck and cap of a bottle or other similar container.

Bands or sleeves of regenerated cellulose are frequently applied to bottle tops to improve the appearance of the bottle, to identify the manufacturer of the product and to make it difficult to tamper with the contents of the bottle. The use of a regenerated cellulose band for this purpose is well-known and such bands are ordinarily supplied by manufacturers in a flattened, hydrated condition covered with water, glycerin or other suitable liquid. Such hydrated bands slip easily over the neck of a bottle and when the band dries it contracts forming a tight seal which prevents the top of the bottle from being removed unless the band is destroyed.

The application of such bands to bottles may be done either by hand or machine, but the machines which have heretofore been suggested are large, expensive and cumbersome so that small manufacturers cannot ordinarily afford such machines and must perform the banding operation by hand. This is a slow and time-consuming process.

It is an object of the present invention to provide a machine for automatically placing regenerated cellulose bands over the necks of bottles.

It is a further object of this invention to provide such a machine which has relatively few moving parts, which is inexpensive to manufacture and which can be used economically by relatively small bottlers.

It is another object of this invention to provide a machine which is fully automatic in its operation and which requires a minimum of attention.

In the drawings illustrating the preferred embodiment of the invention, Figure 1 is a perspective view of a band applying machine and Figure 2 is a front elevation view, partly in cross section of the rotor and its accessory equipment which has been designated 7 in Figure 1.

Referring now to the drawings by reference characters, there is shown in Figure 1 a conveyor 3 for moving filled and stoppered bottles 5 into the band applying position of my machine. Mounted over conveyor 3 is the actual band applying mechanism which has been designated generally 7, which has in association therewith a further mechanism for supplying individual and opened bands which have been designated generally 9.

The band delivering and opening mechanism 9 consists of a magazine 11 which is of suitable size to receive a number of folded bands of regenerated cellulose 13. Magazine 11 has a slot

15 near its bottom, said slot being of such dimensions that only one folded band at a time may be passed through it. The folded cellulose bands 13 are placed in magazine 11 so that an open end of each band faces slot 15. A slide 17 is mounted at the bottom of magazine 11 and is adapted to slide in guides 19 at the bottom of the magazine and to eject the folded bands from the magazine one at a time. The slide 17 is actuated by an air cylinder 21 from a controlled source of air 23.

As the bands 13 are ejected from the magazine 11, the bands are picked up on endless chain 29 and carried toward the opening mechanism which has been designated generally 21. To prevent slippage, chain 29 may be provided with cross members 26. The opening mechanism 21 has a prime mover 29 which drives roller 31 and the endless chain 29. Roller 31 is preferably knurled or milled with a series of ridges, as illustrated, so that it will grip the cellulose bands firmly. Mounted over the roller 31 and in a close proximity thereto is a drag roller 33. Roller 33 is made of rubber or other suitable substance which exerts a gripping or braking effect on the cellulose bands. Roller 33 is either fixed in place or provided with bearings having considerable friction so that it turns with difficulty. As a band is conveyed by chain 29 it is gripped between rollers 31 and 33; the bottom surface of the band is urged forward by roller 31 while the top surface of the band is retarded by roller 33. This causes the band to slip upon itself and open up as is shown by the band designated 35 in the drawing.

The rotor which has been designated generally 7 is mounted for rotation on a bearing 37, its direction of rotation being counter-clockwise in both figures. The rotor 7 has a plurality of arms or spokes 39, suitably four in number, and each spoke has a circular radial hole therein, the diameter of the hole being relatively small near the center of the rotor, substantially larger for an intermediate distance and still somewhat larger at the periphery, as shown. Mounted in each of the peripheral holes of the rotor are sleeve members 41. Each sleeve 41 has an annular collar 43 which extends beyond the rim of rotor 7, as shown. Each sleeve 41 is held in the retracted position with its collar 43 against the rim of rotor 7 by means of two springs 45. Fitting within sleeve 41 is a tubular band receiving member 47. The band receiving member 47 is fixed in place in the rotor 7 at the end near the axis of the rotor, but there is sufficient clearance between member 47 and sleeve 43 to permit sleeve 43 to slide freely over the band receiving member. The outer diameter

of the band receiving member 47 is such that it will receive a band snugly, at its largest point. The portion of receiving member 47 which extends beyond rotor 7 is tapered, as is shown at 49, so that a band may be readily slid over member 47. Member 47 is hollow and has an annular abutment 50. Slidably mounted within the band receiving member 47 is a prong 51 which terminates at its outer end in tip 53, which is adapted to engage the open portion of a band and is substantially smaller in diameter than an expanded band so that the band can be engaged by the tip 53 when only partially opened. The lower portion of prong 51 has an annular abutment 55, which is adapted to engage against abutment 50 preventing the prong from being completely withdrawn from the band receiving member 47. The shoulder between the body of prong 51 and its tip 53 is suitably curved so that when the prong is in the extended position, the taper 49 of band receiving member 47 and the extended portion of prong 51 form a matching, smooth surface. Attached to the prong 51 is a shaft 57 which serves to guide the movement of the prong. Mounted over shaft 57 is a spring 59, which tends to keep the prong in an extended position. Mounted within rotor 7 is a detent member 61 which is slid- able for movement in a slot 63. Detent 61 is limited in its movement by the depth of slot 63 so that it cannot go beyond the center of the hole 65 through which shaft 57 slides. Detent 61 is held in its extended position by a spring 67, and the edge of detent 61, which faces shaft 57, is tapered as is shown. The end of shaft 57 is pointed and is provided near the point with an annular recess 69. Thus, when some force pushes prong 51 into the retracted position, the pointed end of shaft 57 pushes detent 61 to one side so that it cannot engage in recess 69. Prong 51 is then locked in a retracted position and cannot be extended until detent 61 has been moved sufficiently to clear recess 69.

To move detent 61 at the proper time and to extend the prong 51, there is provided a rotating tripping member 71 mounted on a shaft 73. When member 71 is rotated 90° in a clockwise direction, it moves detent 61 upwardly clearing recess 69 and permitting the spring 59 to bring the prong 51 into the extended position.

For the purpose of pushing the open bands onto the band receiving member and also pushing the bands from the band receiving member onto the neck of a bottle, rod 75 is provided which has attached thereto two arms 77 and 79. Rod 75 is adapted for vertical reciprocation in the manner hereinafter described. Arm 77 is of sufficient length and breadth to substantially cover a band 81 placed on the band receiving member 47. Arm 79 is shorter and is adapted to engage the collar 43 on sleeve 41.

The over-all operation of the device is as follows: Air, from a source not shown, is forced through line 23 into cylinder 21 actuating slide 17, which pushes a single folded band from the magazine 11 onto the endless chain 29. The endless chain 29 carries the band to the opening mechanism 27 where it is opened by the combined action of roller 31 and 33 as heretofore described. As soon as the band 35 is at least partially open, the member 71 is rotated 90°, as is shown in dotted lines at 71a, tripping detent 61 and allowing prong 51 to go from the retracted to the extended position, whereupon the tip 53 of prong 51 engages the open portion of the band 35. Rotor 7 is then rotated through 90° counter-clockwise so that

prong 51 is in the upright position. At this point it is apparent that the tip 53 of prong 51 will hold the band loosely. At this time, rod 75 moves downward and the action of arm 77 forces the band from its loosely held position on the tip of prong 51 into a snug position around band receiving member 47, as is shown at 81 in Figure 2. At the same time that arm 77 is forcing band 81 onto the band receiving member 47, it also contacts the tip 53 of the prong 51, pushing it downward so that detent 61 is brought into engagement with recess 69, again locking the prong 51 into the retracted position. Rotor 7 is then rotated 180° so that the band receiving member 47 which has a band 81 thereon faces downward. In the meantime, the conveyor 3 has advanced the bottles 5 which are to be banded, so that one of the bottles, designated 5a, is directly under the band receiving member 47. Rod 75 then moves downward causing arm 79 to engage collar 43 and to force the band 81 from the band receiving member 47 onto the neck of the bottle 5a, as is shown at 83. As the arm 75 is raised, the springs 45 urge the sleeve 41 back into a retracted position so that all parts are in position for a repetition of the cycle upon the rotation of rotor 7 through 90°.

Although only a single operation has been described at each position of the rotor, it is obvious that other operations are being conducted simultaneously at the other stations. For instance, a single movement of rod 75 downward not only pushes a band onto a bottle, but also pushes another band onto the band receiving member and resets the prong.

I claim:

1. In a band applying machine having means for opening and supplying a single band, a rotor having a plurality of arms, each of said arms having a circular radial opening therein, a movable sleeve having a collar thereon said sleeve fitting into said circular opening and limited in its inward movement by the collar, a fixed band receiving member within said sleeve and concentric thereto, and an extendable prong concentric with and inside said band receiving member, means for extending said prong to engage and receive a partially opened band, means for pushing said partially opened band from said prong onto the band receiving member, and means for extending said sleeve whereby a band on the band receiving member is moved off of the band receiving member and onto the neck of a bottle.

2. A machine for applying a contractable ring-like band to the neck of a bottle comprising a magazine for holding a supply of folded bands, means for removing a single band from the magazine and opening said band, a rotatable annular member having a radial opening therein, an extendable prong slidably mounted in said radial opening said prong being adapted to be extended into a waiting band, a band receiving member concentric with said prong, said band receiving member being fixed in said radial opening, means for pushing a band from the prong to the band receiving member, and a concentric collar fitting over said band receiving member and adapted to slide along the band receiving member and to push the band from the band receiving member onto the neck of a bottle.

3. A machine for applying a contractable ring-like band to the neck of a bottle comprising a magazine for holding a supply of folded bands, a slide operable in said magazine to push a single band from the magazine, a conveyor adapted to

receive a folded band, two rollers at the discharge end of said conveyor on axes at right angles thereto, one of said rollers being placed above and the other roller being placed below the normal path of travel of said conveyor, one of said rollers being driven and serving to convey the band between said rollers and the other roller being an idler roller adapted to retard the opposite side of a band, whereby a band is opened, a rotatably mounted annular member having a radial opening therein, an extendable prong supported in said opening, said extendable prong being adapted to receive an open band, a band receiving member concentric with said prong, means for pushing an open band from the prong to the band receiving member, and a collar fitting over said band receiving member and adapted to slide over the band receiving member and to push the band therefrom and onto the neck of a bottle.

4. In a band applying machine having means for opening and supplying a single band, a rotor having a plurality of arms, each of said arms having a circular radial opening therein, a movable sleeve having a collar thereon said sleeve fitting into said circular radial opening and limited in its inward movement by the collar, a fixed band receiving member inside of said sleeve and concentric therewith and a movable prong concentric with said sleeve and said band receiving member, said prong being located inside said band receiving member and concentric therewith, and being adapted to receive a partially open band, means for retracting said prong and pushing an

10
1520
25
30

open band onto said band receiving member, said movable sleeve fitting over said band receiving member and sliding thereon and adapted to push the band from the band receiving member.

5. A device for feeding and opening contractable bands comprising a magazine for holding a supply of folded bands, a slide operable to eject a single band from said magazine, a conveyor adapted to receive said single band, upper and lower rollers mounted at right angles to said conveyor and adjacent to the discharge end thereof, the upper roller being located just above the path of travel of said conveyor and the lower roller being located below the path of said conveyor, said upper roller being an idler roller and adapted to retard one side of a band and said lower roller being a driven roller tending to propel the opposite side of said band whereby the band is opened.
